FUEL DISTRIBUTOR

Joseph J. Kress, Erie, Pa., assignor to The Standard Stoker Company, Incorporated, a corporation of Delaware

Application July 26, 1938, Serial No. 221,303

6 Claims. (Cl. 110—105.5)

This invention relates to stokers of the type delivering fuel from a source of supply to a distributing means at the firing opening in a furnace wall.

An object of the invention is to provide a stoker mechanism of the type described for uniformly and continuously distributing fuel over all parts of the firebed in the firebox.

Another object of the invention is to provide in a stoker of the type described, means for varying the relative amounts of fuel delivered onto various parts of a fuel receiving plate, from which plate the fuel is projected over various parts of the firebed in desired quantities.

Another object of the invention is to provide conveniently adjustable deflecting means at the delivery end of a stoker arranged to act on the fuel prior to its delivery into the zone of action of the projecting means for effecting heavier or lighter firing of fuel to either side of the firebox as required.

The invention accordingly consists in the construction of elements and arrangement of parts hereinafter described and claimed and as illustrated in the accompanying drawings, in which

Fig. 1 is a vertical longitudinal central section through the upright wall of a boiler firebox with the device of the invention applied thereto and shown in similar section;

Fig. 2 is a view in elevation looking through the firing opening in the upright wall from within the firebox, showing the device of the invention applied thereto, parts being broken away and shown in section; and

Fig. 3 is a sectional view taken on the irregular line 3—3 of Fig. 1.

For purposes of illustration the invention has been shown as applied to the backwall of a locomotive firebox, but it will be apparent that it is equally applicable to furnaces of other types.

In the drawings a boiler firebox is shown at 10, provided with a backwall 11 having a firing opening 12, therethrough. Fuel is delivered to the firing opening from a source of fuel supply by a stoker, indicated generally by the numeral 13. Only so much of the stoker as is essential to a complete understanding of the invention is shown, the rearward portion of the stoker being of any suitable construction well known in the art.

A housing 14 embraces the firing opening and is rigidly secured to the backwall 11 by means extending through the flange 15. The rear wall of the housing 14 is provided with an opening 16 in substantial register with the firing opening 12

and a conventional form of firedoor 17 forms a closure for the opening 16. Communicating with the bottom of the housing 14 is a downwardly and rearwardly extending tubular portion 18, preferably formed integral with the housing 14. A conduit 19 communicates with the lower end of the tubular portion 18 and is rigidly secured thereto by means of bolts 20 passing through the flanges 21 and 22 extending circumferentially of the adjacent ends of the tubular portion 18 and conduit 19, respectively. The conduit 19, tubular portion 18 and housing 14 constitute a fuel feed conduit through which fuel is advanced by a screw conveyor 23.

The housing 14 and tubular portion 18 is recessed or cut away adjacent the lower marginal edge of the firing opening 12 to receive the chambered jet table 24 which forms a continuation of the bottom of the tubular portion 18 and is provided at its forward end with jet openings 25 in the upright front face 26. The front face 26 comprises a central face portion 27 and side face portions 28 and 29 sloping outwardly and rearwardly from the ends of the central face portion 27. The jet openings 25 are drilled substantially perpendicular to the face portions in which they are formed, so that the jet openings in the side face portions 28 and 29 are directed toward the side portions of the firebox while the jet openings in the central face portion 27 are directed across the central portion of the firebox. Fluid under pressure is delivered to the chambered jet table 24 from a suitable source of supply by a pipe 30.

The jet table 24 is provided with a ledge 30 extending forwardly of its front face 26 from the under side thereof on which is seated the distributing table 31. The distributing table 31 is provided with a rearwardly extending ledge 32 resting against the underside of the jet table 24. Pins 33 extending through the distributing table 31 and the jet table ledge 30 prevent forward movement of the table 31 with respect to the jet table 24. The upper surface of the distributing table 31 is provided with upstanding ribs 34 and 34a curving forwardly and laterally away from each other and increasing in height from their respective rearward ends to their forward ends. The ribs 34 and 34a serve to deflect a portion of the fuel projected across the table 31 by the pressure fluid emitted from the jet openings 25 toward the rear corners of the firebox.

At times it is necessary to deliver more fuel to the sides and rear corners of the firebox than along the central portion thereof, or it may be

necessary to deliver more fuel to one side or rear corner than to the other side or rear corner of the firebox. For this purpose I have provided a simple, practical and efficient means that is conveniently adjustable without disturbing or dismantling any part of the stoker.

In each lower side of the housing 14 and extending along the sides of the tubular portion 18 are formed longitudinally extending inclined seats or recesses 35 and 36. These seats or recesses are arcuate shaped in transverse cross-section and the upper surface of the jet head 24 on each side of the central face 27 is provided with similar concave recesses 37 and 38 forming continuations of the seats 35 and 36, respectively.

Cylindrical members 39 and 40 are rotatably mounted in the seats 35 and 36, respectively, and extend forwardly to approximately the plane of the central front face 27 of the jet head 24. The cylindrical members 39 and 40 are formed with facets 41 and 42 respectively, forming with the top surface of the jet head 24 a passage for the fuel. By rotating the cylindrical members 39 and 40 about their respective axes, their faceted portions can be made to cover the concave recesses 37 and 38 completely or uncover them a desired amount. The cylindrical members 39 and 40 are provided with rearwardly extending stems 43 and 44, respectively, extending exteriorly of the stoker and by turning the knobs 45 and 46 mounted on the projecting portion of the stems 43 and 44, respectively, the cylindrical members 39 and 40 can be adjusted to any desired position.

With the cylindrical member 39 in the position shown in Figs. 2 and 3, the recess 37 is completely cut off, so that only small amounts of fuel will fall on the distributing table 31 in front of the jet openings in the face 28 of the jet table 24 and consequently a relatively small amount of fuel will be projected to the right side and rear corner of the firebox. With the cylindrical member 40 in the position shown in Figs. 2 and 3, the faceted portion thereof uncovers a part of the recess 38, so that fuel received in the recess falls on the distributing table 31 in front of the jet openings in the face 29 of the jet table 24 and is projected across the distributing table 31 and deflected by the rib 34a to the left side and rear corner of the firebox. Thus by adjusting the cylindrical members 39 and 40 to uncover more or less of the recesses 37 and 38, more or less fuel can be delivered to either side and rear corner of the firebox as required.

I claim:

1. In combination, a firebox having a wall with an opening therein, a stoker fuel feeding conduit having its discharge end communicating with said opening, means for advancing fuel through said conduit, a pair of laterally spaced longitudinally elongated concave recesses formed in the lower portion of said conduit adjacent its discharge end, a longitudinally extending deflector member disposed in each of said recesses, said deflector members forming side walls of said conduit, said walls having substantially upright forward edges and longitudinally extending upper edges, said forward edges defining an outlet opening, said walls defining in the direction of extent of the deflectors an unobstructed path of travel whereby substantially all of the fuel is confined between said walls and passes between said forward edges, a portion of said deflector members having a surface concentric with said concave recess, and means for rotating said deflector members about

their longitudinal axes to expose a portion of said concave recesses.

2. In combination, a firebox having a wall with an opening therein, a stoker fuel feeding conduit 5 having its discharge end in communication with said opening, means for advancing fuel through said conduit, a fuel distributor including a jet head forming a floor portion of said conduit at its discharge end, a longitudinally elongated concave recess formed in the top surface of said jet head adjacent each lateral extremity thereof, a longitudinally extending deflector member disposed in each of said recesses, said deflector members forming side walls of said conduit, said walls having substantially upright forward edges and longitudinally extending upper edges, said forward edges defining an outlet opening, said walls defining in the direction of extent of the deflectors an unobstructed path of travel whereby substantially all of the fuel is confined between said walls and passes between said forward edges, each of said deflectors being mounted for rotation about a longitudinally extending axis to expose said recesses a desired extent the exposed portions of said recesses forming fuel supporting parts of the passage along which the fuel is advanced to the discharge end of the conduit.

3. In combination, a firebox having a wall with an opening therein, a stoker fuel feeding conduit 30 having its discharge end communicating with said opening, means for advancing fuel through said conduit, a pair of laterally spaced longitudinally elongated concave recesses formed in the lower portion of said conduit adjacent its discharge end, a longitudinally extending deflector member disposed in each of said recesses, said deflector members spaced a substantial distance apart throughout their longitudinal extent and being generally cylindrical in shape, a portion 35 of the curved surface of each of said deflector members being cut away forming facets, said facets forming with the bottom wall of said conduit a trough-like passage for the fuel, and means for rotating said deflector members about their longitudinal axes to expose a portion of said concave recesses.

4. In combination, a firebox having a wall with an opening therein, a stoker fuel feeding conduit 40 having its discharge end communicating with said opening, means for advancing fuel through said conduit, a fuel distributor jet head forming a floor portion of said conduit at its discharge end, a longitudinally elongated concave recess formed in the top surface of said jet head adjacent each lateral extremity thereof, a deflector member disposed in each of said recesses, said deflector members being generally cylindrical in shape, a portion of the curved surface of each of said deflector members being cut away forming facets, said facets forming with the top surface of said jet head a passage for the fuel, and means for rotating said deflector members about their longitudinal axes to expose a portion of said concave recesses.

5. In combination, a firebox having a wall with an opening therein, a stoker fuel feeding conduit having its discharge end communicating with said opening, means for advancing fuel through said conduit, a fuel distributor jet head forming a floor portion of said conduit at its discharge end, said head having a front face provided with a plurality of jet openings, a distributor plate extending forward from said face below said jet openings, a longitudinally elongated concave recess formed in the top surface of said jet head adjacent each

lateral extremity thereof, a deflector member disposed in each of said recesses, said deflector members being generally cylindrical in shape, a portion of the curved surface of each of said deflector members being cut away forming facets, said facets forming with the top surface of said jet head a passage for the fuel, and means for rotating said deflector members about their longitudinal axes to expose a portion of said concave recesses.

6. In combination, a firebox having a wall with an opening therein, a stoker fuel feeding conduit having its discharge end communicating with said opening, means for advancing fuel through said

5 conduit, a pair of laterally spaced longitudinally elongated concave recesses formed in the lower portion of said conduit adjacent its discharge end, a longitudinally extending deflector member disposed in each of said recesses, said deflector members having their respective adjacent faces diverging toward the discharge end of the conduit and forming side walls of said conduit defining therebetween the path of travel of substantially all the fuel through the conduit, and means for rotating said deflector members about their longitudinal axes to expose a portion of said concave recesses.

JOSEPH J. KRESS.
